UNITED STATES PATENT OFFICE

HARRY BARLOW, OF PORT MADISON, WASHINGTON, ASSIGNOR TO BARLOW MARINE ELEVATOR CO. INC., OF SEATTLE, WASHINGTON, A CORPORATION OF WASHINGTON

MARINE ELEVATOR

Application filed December 16, 1926. Serial No. 155,212.

- My invention relates to a marine elevator. More particularly my invention relates to an elevator whose platform may be moved endwise both when stationary as respects a given level and while elevating or lowering, and which may be employed as an inclined slip or way, and when the platform is not in use may be positioned beneath the dock deck so that the deck is left clear.
- 10 For purposes of clearness and definiteness of illustration I will describe a marine application of my invention under conditions obtaining on a dock to which a vessel may be moored for purposes of loading or unloading. My invention is directed particularly to solving the problem of loading and unloading vessels where there is tidal variation. This term "tidal variation" herein includes both the difference in the level of 15 fresh water in rivers or lakes where spring freshets and the summer droughts produce great variation in the levels of the water as well as where variation is due to true tidal action obtaining in salt water.
- 20 At the present time, one or more railroad tracks are commonly located lengthwise of the dock between the dockshed proper and the outer edge of the dock. It will be understood that the elevator is disposed transversely of these tracks, and it becomes necessary, therefore, to remove that section of the dock floor including said tracks, which section is immediately disposed above the elevator. This section must be moved and maintained out of the way before the elevator platform can be put into operation for loading or unloading. A primary object of my invention is to provide an elevator which accomplishes this by elevating said section of 25 the dock deck so that said elevated section may not only be disposed in a position where it will not interfere with the operation of the elevator platform, but also may be used directly as a bridge across which passengers or 30 freight may move to the second floor of the dockshed while the elevator platform itself is being used to remove freight or passengers from a lower deck of the vessel. A further condition obtains on marine docks in that it 35 is important to have the dock outside of the dockshed free of all elevator or other structures above the level of the dock thereby providing free and ready access to all parts of the dock with varying forms of freight and particularly eliminates all interfering structures for traveling cranes, so that a primary purpose of my invention is to provide an elevator which may be disposed beneath the dock level when not in operation.
- 40 A primary object of my invention is to provide an elevator which satisfies the necessity of spanning the distance between the edge of the dock and the vessel owing to the common practice of disposing fender logs along the water side of the dock to hold the vessel 45 at a distance therefrom to protect the vessel's outside rigging. Not only is this swinging out and in of the elevator platform essential, but it is necessary that said outward and inward swinging be possible as 50 different elevations of the platform with different degrees of magnitude of said outward and inward swinging at said different elevations in order that the changing level incident to the tide may be fully satisfied.
- 55 This inward and outward swinging of the elevator platform is necessitated in part by the fact that the vessel may have a flaring hull wall forward of midship, and a fairly straight hull wall aft, hence, it is necessary 60 to have an elevator that may be adapted to swinging outwardly and inwardly to contact the different decks and the different port openings as well as clear the different decks 65 while moving down and up. One purpose of 70 my invention is to accomplish this end.
- 75 A primary purpose of my invention is to provide an elevator having automatically operating safety means to avoid injuring operators.
- 80 A primary purpose of my invention is to provide an elevator platform which may be used as an inclined slip or ramp under the following circumstances: (1) Where the variation in the level of the dock deck and that of 85 the vessel is relatively small and the truckers can easily operate over the platform when inclined; (2) When it is desired to load passengers from different decks of the vessel, the elevated section being employed as a passage- 90
- 95
- 100

way on the upper deck and the ramp for the passengers on the lower deck; (3) For unloading sheep or cattle, whereby said animals may continue in motion when once they are started to be unloaded; (4) When there is fire on the dock and the electrical cables conducting power to the dock are damaged, so that the elevator mechanism is out of order, then the elevator platform herein described may be disposed manually into an inclined slip or ramp position, so that the loading or unloading of the vessel by way of escape for the passengers may proceed without interruption.

18 In operating as a slip provision should be made for the elevator platform to be inclined from the dock level to the deck of the ship and also should be adapted to be inclined to the dock deck from the deck of the vessel. A primary purpose of my invention is to provide an elevator which will satisfy these conditions.

25 A further primary object of my invention is to provide an elevator characterized by its simplicity in construction and efficiency in operation. The drum upon which the hoisting cables are wound are preferably disposed upon one shaft and at the same time provision is made for keeping the cables taut at all times and free from fouling.

30 A further condition which is important in an elevator used for dock purposes is that the elevator platform should be free on all four sides, there being certain commodities of freight which are customarily stored outside of the dockshed, and, therefore, ready access must be had to the elevator platform not only across the ends, but also the sides, of the platform. A primary purpose of my invention is to provide an elevator platform which is substantially clear on all four sides.

35 Also, a fundamental condition in marine elevators is flexibility, because the members of a dock and of construction mounted thereon are subject to being displaced by impact with the incoming vessel or by strains arising at the time of mooring. Lines being secured to the dock on both sides of the elevator for mooring the vessel often are wound in by the winches which tends to spring and distort the elevator opening and mounting structure. A primary purpose of my invention is to overcome this difficulty by providing an elevator which is suspended by flexible connections and also an elevator which in its various movements as throwout etc., is guided by flexible connections so that the operation of the elevator is rendered independent of the dock being distorted as indicated, there being no guides requiring nicety of fittings which would tend to bind the elevator platform in the event of the dock being put out of line.

40 Finally, a primary object of my invention is to provide an elevator which is characterized

45 by its provision for safety to the men employed, to passengers and freight by eliminating the human element.

50 The above mentioned general objects of my invention together with other inherent in the same, are attained by the mechanism illustrated in the following drawings, the same being preferred exemplary forms of embodiment of my invention, throughout which drawings like reference numerals indicate 55 like parts:

55 Figure 1 is a view in side elevation of a marine elevator embodying my invention with the dock deck in normal position when the elevator platform is not in operation, the platform being in lowered position;

60 Fig. 2 is a side view of the same, showing the dock deck elevated by means of the platform to its upper position, to permit of the use of the platform thereunder;

65 Fig. 3 is a view in longitudinal section of the same with the platform in operative position with respect to the lower deck of a vessel;

70 Fig. 4 is a longitudinal sectional view of the same showing the elevator platform disposed as an inclined slip or ramp;

75 Fig. 5 is a fragmentary plan view of the hoisting drums and power means;

80 Fig. 6 is a sectional view on line 6.6 of Fig. 1.

85 Fig. 7 is a cross section of the telescoping guide members on dotted line 7.7 of Fig. 1;

90 Fig. 8 is a view in side elevation of the telescoping member;

95 Fig. 9 is an end view of a marine elevator embodying my invention;

100 Fig. 10 is a side view of hatchway limiting switch;

105 Fig. 11 is a fragmentary view of roller mounting means for the apron; and

110 Fig. 12 is a side view of the holding means which maintains the outer end in elevated position.

115 Piling (8) wooden or concrete, supports the usual dock deck (9). The motor (10) and directly associated gear mechanism is disposed within the dockshed (11) (see Figs. 1 and 9). Between the dockshed (11) and the outer edge (12) of the dock, there may be disposed one or more railroad tracks (13). A crane track (14) (one rail of which may be disposed on the dockshed roof (not shown) and one near the outer edge of the dock) provides for the dock supplementary unloading mechanism in addition to the elevator mechanism, said supplementary mechanism being employed for special types of freight.

120 A section (15) of the dock which is disposed immediately over the elevator platform (16) is provided with supporting guide posts (17) fixedly mounted thereon. These may be slidably disposed in dock frame (18). When the section (15) is in elevated position the ends of said posts (17) rest in removable

supports (19). These supports (19) may be pivotally mounted at (20) and may be connected by rods (21 and 22) to lever (23) mounted on shaft (24) which shaft (24) is connected to the rods (21 and 22) on the opposite side by the short link (25) (Fig. 3). The removable supports have upturned edges (26) to form pockets in which the ends of the guide posts (17) seat. This provides a safety feature against any movement of the lever (23) until the weight of the section (15) is carried by the elevator platform (16). Manifestly any attempt to move the lever while the weight of the section (15) rests in said pockets would cause the flanges of the seat to strike against the end portions of the posts (17). This feature then requires the operator to see that all truckers are off the elevator platform before he undertakes to move lever (23) and as he must lift section (15) by means of the elevator platform it is manifest he would necessarily first clear the elevator platform of all operators before moving lever (23). If it were not for this safety feature it might happen that the lever (23) would be actuated unintentionally to remove the supports of the guide posts and permit the section (15) to fall by gravity upon operators working on the elevator platform. This platform (16) is provided with lifting supports (27) which are preferably located on one end only, and this at the outer end; but, manifestly, they could be provided at other points as at the inner end, or at both ends.

The platform is provided with apron (28) which has upstanding mounting members (29) (Fig. 11). In these upstanding mounting members is a shaft (30) on which are wheels (31) and these in turn are operatively disposed in guides (32). Roller (33) on the end portion of the platform facilitates the sliding of the apron endwise of the platform to connect with the deck of the vessel. This apron normally resting on the floor of the elevator platform is manifestly adapted to be moved endwise to extend the platform to such extent as may be required.

Hoisting drums (34 and 35) fixedly mounted on the shaft (36) are adapted to receive the hoisting cables (37 and 38) secured to the inner end portion of the elevator platform, and also cables (39 and 40) which are operatively secured to the outer end portion of the platform. Cable sheaves (41 and 42) are mounted in dock frame (18) for guiding hoisting cables (39 and 40). Hoisting cables (37 and 38) (Fig. 4) may be secured to a counterweight (43), the cables being disposed to freely pass through openings (44) in the platform (16). Likewise hoisting cables (39 and 40) may be connected to counterweight (45) which is operatively connected to the lower end portions of lifting supports (27) by means of the eyes in

lugs (46). This arrangement of the counterweights being secured to the cables, which have a sliding engagement with the platform parts, provides positively for the cables to be at all times connected to the platform, and thus a safety feature is assured. Counterweights (43 and 45) function to keep hoisting cable lines taut at all times when the elevator is used as an inclined slip or ramp as hereinafter described.

The telescoping guides, which prevent sidewise swinging of the elevator and compel the longitudinal axis of the platform to move in one vertical plane, have a fixed member (47) (Fig. 7) and movable member (48).

The movable telescoping guide members (48) have projecting flanges (49) which engage the top portion of the elevator platform (16) whereby said guide members are carried with the platform when it moves upwardly.

Shaft (36) (Fig. 5) is connected through gear (78) to a worm gear (50) which provides the well known self-locking effect and this in turn is connected by suitable gear mechanism (51) to motor (10). Drums (34 and 35) are preferably provided with counterweights (53 and 54). Standard automatic hatchway limit switch (55) (Fig. 10) is tripped by member (56), said switch being electrically connected with a standard brake (57) so that the motor is automatically stopped when it is desired to prevent the platform (16) from rising above a predetermined position such as the level of the dock. When it is desired to have the elevator move above such point, the switch is manually operated to permit such rising of the elevator which would be necessary in the present instance to allow the elevator to move up to engage the underside of section (15) to lift said section so that it can be lowered into position as will be hereinafter more fully described. Such standard automatic hatchway limit switch may likewise be provided for the dock section (15) which positively prevents any accident occurring from unduly elevating the dock section while the elevator platform hatchway limiting switch is being manually held open.

The throwout mechanism will next be described. A connector means on each side of the elevator platform as a cable (58) is secured to bracket (59) at one end of the elevator, and the other end of said connector means is secured to flange (49) of the movable members (48) of the telescoping guides. A fixed guide means (60) (Fig. 1) is provided extending from the dock frame (18) downwardly for a sliding member (61) which is pivotally connected with push-bracing arm (62) on the opposite end to the movable members of the telescoping guides (48) (Fig. 4).

A sheave (63) (Figs. 1 and 4) is mounted

near the top of guide (60) over which cable (64) passes to sheave (65) to drum (66) which may be actuated by means of a crank (67). A cable means similar in all respect to (64) is disposed on the opposite side of the elevator. The lower end of this cable (64) is connected to a counterweight (68), the cable passing through an eye (69) in the mounting of member (61).

10 The connector means (58) telescoping movable member (48), push-bracing arm (62), guide (60), and the cable (64), and its associated sheaves and drums constitute the adjustable "throwout mechanism" of the elevator, i. e., by this means the elevator platform (16) may be caused to move outwardly to span the space between the dock and the deck of the vessel which may be held away from contacting the dock by means of fender logs (70), abutting against fender pile (79).

When it is desired to convert the elevator platform (16) into an inclined slip or ramp, the elevator platform (16) is moved to a position above the level of the dock and a lever (71) is turned to throw out holding mechanism (72) (Fig. 4) which is here shown in the form of dogs which engage end plate (73) secured to the platform.

When it is desired to have the outer end of the elevator platform in elevated position with respect to the level of the dock, a holding means (74) (Fig. 12) here illustrated as a chain, one end being secured to the lower end portion of the lifting supports (27), is secured to the dock frame (18) by hook (77) (thereby being adjustable since it is possible to hook any of the links of the chain 74 in the hook 77) so as to maintain said outer end of the elevator in elevated position as may be desired.

An apron (75) with similar mounting means in all respects to apron (28), is provided on the dock level.

The operation of many parts of the elevator embodying my invention has already been described, so there remains to be described only the mode of operating the elevator as a whole.

Assuming that the level of the deck of the vessel is below the level of the dock as illustrated in Fig. 1, the first step is to lift the dock section (15) in the elevated position so that the elevator platform (16) will be free to be employed in lifting freight from the level of the deck of the vessel to the level of the dock. To do this the elevator platform (16) being disposed against the under side of the dock section (15) as shown in Fig. 2, is elevated by means of causing the motor (10) to

60 actuate hoisting drums (34 and 35) which wind up the inner and outer hoisting cables (37, 38, 39 and 40). Thus dock section (15) is lifted to elevated position shown in Fig. 2, and when elevated the lever (23) is actuated 65 to bring the removable supports (19) direct-

ly beneath the posts (17) and then the elevator platform is lowered and the posts (17) descend into seating position in the pockets formed by the flanges (26). In this manner the dock section (15) is maintained in elevated position out of the way of the working of the elevator platform thereunder. This elevated dock section (15) may be employed to permit the unloading of passengers from an upper deck of the vessel to the second floor 75 of the dockshed, (not shown), or freight may be trucked across this elevated dock section. Furthermore, said elevated dock section is useful as a covering against rain and storm while the unloading of freight by the elevator is in progress. The elevator is then lowered below the level of the dock and apron (75) is caused to extend over the elevator platform opening (76), commonly known as "well" 80 opening. Likewise apron (28) is pushed outwardly. Likewise apron (28) is pushed outwardly.

The flange (49) on telescoping movable member (48) is now lowered by means of crank (67) to the position taught by experience to give the necessary throwout to the elevator platform (16) to bring the outer end of the platform in engaging position with the deck of the vessel by means of the apron (28). The dotted curved line Fig. 3 indicates the path of travel of the platform from the level of the vessel's deck to the level of the dock. It is manifest that the point at which the elevator platform begins to throw out depends upon the level at which the flange (49) is disposed. Since the connector means (58) establishes a fixed relation between the bracket (59) and the flange (49), flange (49) being the point about which the bracket (59) oscillates with the connector means (58) representing the radius. Manifestly, therefore, the degree of throwout of the elevator platform as well as the point at which said throwout is to take place, can both be readily adjustable by means of the throwout mechanism herein described. If it is desirable to have the throwout begin near the level of the hoisting sheaves (41 and 42) it is necessary to extend the telescoping movable members (48) above the level of the dock. To provide the proper brace for these supports while thus elevated the push-bracing member (62) is provided—the fixed guide (60) functioning as a base against which said push-bracing arm may operate in supporting the telescoping movable members (48). This construction of the throwout means is characterized by a smoothness of throwout movement as contrasted with a sudden jolt action at the commencement of the throwout.

The mode of operation of the elevator when it is desired to be used as a slip or inclined ramp extending from the level of the dock to the level of the vessel is as follows: The elevator platform is elevated to a position above the level of the dock and lever (71) is 125

actuated to move holding mechanism (72) into a forwardly directed position where it will engage end plate (73) and hold this end of the elevator with a fixed pivoted movement. The counterweight (43) to which the inner hoisting cables (37 and 38) are attached, moves downwardly thereby maintaining said cables in taut relation and the elevator platform (16) is thus converted into a rigidly disposed inclined slip or ramp. When it is desired to have the outer end of the elevator platform (16) in a position above the level of the dock so that the elevator platform (16) is to serve as an inclined slip or ramp down to the level of the dock, the elevator platform (16) is moved up to the elevated position desired and the chain (74) is secured to the dock frame (18) by means of a hook (77) and then the hoisting cables are paid out which lets down the inner end of the elevator platform (16) until it engages the holding means (72). With the elevator platform in this position the counterweight means (45) would descend below the lower end portions of the lifting supports (27) thereby maintaining the outer hoisting cables (59 and 40) taut.

The final step would be to replace the dock section (15) into position. This is done by causing the elevator platform (16) to move up against the dock section (15) and lift it slightly to assume its weight, whereupon the lever (23) is actuated to move the seats of the removable supports from immediately beneath the posts (see Fig. 1) whereupon the elevator is lowered and thereby carrying down with it the dock section (15) until it resumes its initial position.

It will be observed that the dock section 15 may be elevated to any desired predetermined level above the main dock floor whereby ample clearance will be provided for using the elevator platform 16 to lift freight above the dock level itself to any desired level as when handling freight to or from a truck.

Obviously, changes may be made in the forms, dimensions, and arrangement of the parts of my invention, without departing from the principle thereof, the above setting forth only preferred forms of embodiment.

50 I claim:

1. A marine elevator embodying an elevator platform having downwardly disposed lifting supports; cable means to raise and lower said platform; drums on which said cables may be wound; power means to actuate said drum; throwout means embodying (a) a telescoping guide composed of a fixed and movable member; (b) connector means joining one end of said elevator platform to one end of said movable guide member; and (c) means to elevate said movable telescoping guide member.

2. A marine elevator embodying an elevator platform having downwardly disposed lifting supports; lifting sheaves; cable means

passing over said sheaves whereby said platform is raised and lowered, said platform being capable of being elevated above said lifting sheaves by means of said lifting supports; drums on which said cables may be wound; power means to actuate said drums; and telescoping guides comprising a fixed and movable member for said platform, said guides having platform engaging means whereby said movable member may be carried up and down. 70

3. A marine elevator embodying an elevator platform; cable means to raise and lower said platform; drums on which said cables may be wound; power means to actuate said drums; and throwout means embodying (a) a telescoping guide composed of a fixed and movable member; (b) connector means joining one end of said elevator platform to one end of said movable guide member; and (c) means to adjustably dispose said movable telescoping guide member, whereby said platform may be moved outwardly at any point intermediate the travel of said elevator and to any extent within a predetermined range. 80

4. A marine elevator embodying an elevator platform; cable means to raise and lower said platform; drums on which said cables may be wound; power means to actuate said drums; and throwout means embodying (a) a telescoping guide composed of a fixed and movable member; (b) connector means joining one end of said elevator platform to one end of said movable guide member; (c) a second guide member; (d) a push-bracing arm having one end secured to one end of said movable guide member and one end slidably disposed on said second guide member; and (e) a cable means whereby said push-bracing arm may be adjustably disposed. 95

5. A marine elevator embodying an elevator platform; cable means to raise and lower said platform; drums on which said cables may be wound; power means to actuate said drums; and throwout means embodying (a) a telescoping guide composed of a fixed and movable member; (b) connector means joining one end of said elevator platform to one end of said movable guide member; (c) a second guide member; (d) a push-bracing arm 100 having one end secured to said movable guide member and having the other end provided with a sliding member operatively disposed to move along said second guide and provided with a cable engaging means; and (e) a cable means whereby said push-bracing arm may be adjustably disposed, said cable being operatively disposed in said cable engaging means of said push-bracing arm whereby the same maintains the said push-bracing arm 115 on a predetermined elevation and said cable having means which keeps the same taut at all times. 120

6. A marine elevator embodying an elevator platform having downwardly disposed 125

lifting supports; inner and outer hoisting cable means to raise and lower said platform; drums on which said cables may be wound; power means to actuate said drums; means whereby one end of said platform may be revolvably supported about a fixed pivot while the opposite end is lowered or raised; and a counterweight means disposed beneath said platform to which the inner hoisting cables are attached, said hoisting cables being free to pass through said platform whereby said cables are maintained taut at all times.

7. Same as claim 6 and, means for compensating the varying lengths of the hoisting cables.

8. A marine elevator embodying an elevator platform having downwardly disposed lifting supports; lifting sheaves; an inner and outer hoisting cable means passing over said sheaves whereby said platform is raised and lowered said platform being capable of being elevated above said lifting sheaves by means of said lifting supports; drums on which said cables may be wound; power means to actuate said drums; means whereby one end of said platform may be revolvably supported about a fixed pivot while the opposite end is lowered or raised; a counterweight means disposed beneath said platform to which the inner hoisting cables are attached, said hoisting cables being free to pass through said platform; a counterweight means disposed beneath said lifting supports to which the outer hoisting cables are attached said hoisting cables being free to pass through their engaging ends of said lifting supports; and means to support one end of said platform above said hoisting sheaves whereby an incline downwardly to the dock level is provided.

9. A marine elevator embodying an elevator platform having downwardly disposed lifting supports; lifting sheaves; cable means passing over said sheaves whereby said platform may be raised and lowered said platform being capable of being elevated above said lifting sheaves by means of said lifting supports; drums on which said cables may be wound; power means to actuate said drums; a movable dock deck section disposed above said platform and engageable by said platform whereby said section may be raised and lowered; supporting guide posts fixedly mounted on said section; supports operatively disposed with respect to said posts whereby said section may be supported in elevated position above said platform.

10. In a marine elevator the combination of an elevator platform having guide members laterally disposed on the end portion thereof and an apron having mounting means secured on the top of said apron operatively disposed in said guide members, whereby said apron is adjustable mounted to swing upwardly above the plane of said platform

at any point of the length of the guide members and provides a continuous deck.

11. In a marine elevator a throwout means embodying the combination of a telescoping guide means and a push-bracing member, ⁷⁰ which member has one end pivotally connected to said guide means.

In witness whereof I hereunto subscribe my name this 2nd day of December, A. D. 1926.
